FUEL DISPENSING COMPUTER UNIT

Albert F. Romanowski, Greeneville, Tenn., assignor to
Bowser, Inc., Greeneville, Tenn., a corporation of
Indiana

Filed July 31, 1962, Ser. No. 71,124

Term of patent 14 years

(Cl. D52—2)

The FIGURE is a perspective view of a fuel dispensing computer unit showing my new design. The two dial and dial casing elements have the same appearance and the opposite side of the support is substantially the same in appearance as the front shown.

I claim:

The ornamental design for a fuel dispensing computer unit, as shown and described.
